UNITED STATES PATENT OFFICE.

JOSEPH SILVERMAN, OF CHICAGO, ILLINOIS.

SHOE-SHINING STAND.

Application filed April 4, 1927. Serial No. 180,700.

This invention relates to shoe shining stands and its objects are the provision of a generally improved and simplified construction that may be economically produced and having a generally improved detachable seat adapted for convenient application and removal and movable into different positions, and an improved foot rest and support extensible and retractible into different positions and adapted for convenient attachment and removal.

The removability of the seat permits use of the stand with or without the seat, and I provide a standardized construction by means of which the stands may be made up and supplied with or without the seat and extensible foot rest, without material alterations.

Where the extensible and retractible aspect of the foot rest is not required, the foot rest is mounted directly upon the stand, and I provide brace means for strengthening the stand when the foot rest is attached directly thereto, this brace means and the extensible foot rest support being selectively applicable without material alteration, whereby the structure is standardized for production with or without the removable seat and extensible foot rest.

The invention is illustrated in the accompanying drawings, in which

Fig. 1 is a top plan view of an embodiment of the present invention;

Fig. 2 is a vertical longitudinal section taken on the line 2—2 of Fig. 1;

Fig. 3 is an end view;

Fig. 4 is a vertical transverse section taken on the line 4—4 of Fig. 2;

Fig. 5 is a detailed section taken on the line 5—5 of Fig. 3;

Fig. 6 is a detailed section taken on the line 6—6 of Fig. 3;

Fig. 7 is a top plan view showing the stand as furnished without the removable seat and without the extensible aspect of the foot rest; and

Fig. 8 is a fragmentary vertical longitudinal section taken on the line 8—8 of Fig. 7.

Referring to the drawings, the stand shown comprises a base-board 5 to the upper surface of which is secured as by screws 6 a second board 7, preferably of less width than the base-board 5 and of less length.

The box 8 is preferably formed of sheet metal of suitable gauge, shaped to generally

U-shape in horizontal section with the open front 9, closed sides 10, 10, closed back 12 and open at the top and bottom. The open bottom of the box 8 fits over the board 7 and is suitably secured thereto as by means of 60 screws 14.

The sides 10 and back 12 have outwardly pressed or offset beads or ribs 15 which impart strength and rigidity to the walls of the box and give the outer surfaces of said 65 walls a finished appearance. The beads or ribs 15, in addition, form depressions horizontally about the interior of the box at different levels.

The interior of the box is divided by 70 shelves 18 into a plurality of compartments 19, 20 and 21 for the shoe shining or other desired articles. The shelves 18 are preferably, likewise, of sheet metal with their side and rear marginal edges turned down to 75 form side flanges 22 and back flanges 23 which fit in the internal horizontal depressions formed by the ribs or beads 15 and are welded or otherwise suitably secured 80 therein to rigidly and fixedly secure the shelves 18 in the box 8. The front marginal edges of the shelves 18 are preferably turned up to form the upstanding front flanges 25 and the marginal edges of the side walls 10, 10 of the box are turned in over 85 the flanges 25 and form vertical marginal flanges 26 along each of the opposite sides at the front.

The outer surfaces of the walls of the box may be suitably finished, as by coloring or 90 blacking the outer surfaces of these walls and polishing the external surfaces of the beads 15. The base-board 5 extends from the front of the box 28 for engagement by the foot of the shiner to prevent tipping of 95 the box when the patron's foot is placed upon the foot rest. The flanges 23 may be doubled, as shown.

The upper marginal edges of the side walls 10, 10 and the upper marginal edge 100 of the back wall 12 are doubled or folded back and welded, or otherwise suitably secured at 30 to the adjacent walls of the box, and are rolled to form the tubular beads or 105 side margins 32 and the tubular bead or rear margin 34. The tubular beads or margins 32 and 34 are open at their opposite ends and where the seat and extensible foot rest are employed, the side margins 32 form a common mounting for both, whereas, where 110

the seat and extensible aspect of the foot rest are omitted, the back bead or margin 34 provides a strengthened marginal support for the fixed foot rest which is attached to the back wall of the box.

The extensible foot rest support 40 comprises a generally U-shaped rod having its legs turned at substantially right angles to from the vertical side legs 42 and the horizontal free ends 43. The horizontal ends 43 fit telescopically in the tubular margins 32 for sliding movement therein to permit positioning the legs 42 at different distances from the box 8, as well as convenient removal and replacement of the extensible foot rest support. The base of the support 40 is arched upwardly at 45 and the semi-circular feet 46 produced thereby may be covered by suitable rubber or other feet or buffers 48 enlarged marginally to fit over and grip the feet 46, with the portions 49 between the raised margins of the feet 48 contracted as shown.

Adjacent the vertical portions 42 the horizontal ends 43 of the legs 40 are provided with a pair of cross pieces 52, 52, the ends of which are partially circular at 53 to embrace the horizontal ends 43 and are clamped together and to the ends 43 as by means of suitable bolts 54. The foot rest 56 has a downwardly curved arm 57, terminating at its lower end in a horizontal base flange 58 secured by bolts 60 to the cross pieces 52, these bolts 60, in addition, aiding in clamping the two cross pieces 52 together.

The foot rest is conveniently adjustable into different positions, as shown in dotted lines, by sliding movement of the horizontal free ends 43 of the support 40 in the tubular side margins 32 of the box 8, and the support ends 43 may be completely withdrawn from the margins 32 and are conveniently insertible therein, as desired.

The seat 65 comprises a base-board 66 of generally rectangular configuration with its under surface recessed at 67 to provide the depending side flanges 68 and the front or end flange 69. The internal surfaces of the side flanges 68 are inclined inwardly and downwardly at 70 for endwise introduction and sliding movement over the tubular margins 32 at the top of the box, and, when engaged with the margins 32, holding the seat firmly in place therein. One end of the recess 67 is open at 72 to permit endwise application and removal of the seat, and the flange 69 at the opposite end may have apertures 73 therein for receiving the rod ends 43 and permitting sliding movement of the same therethrough. This mounting of the seat permits it to be conveniently adjusted to different positions by sliding movement upon the top of the box (as shown in dotted lines) and it permits convenient application of the seat to the box and convenient

removal of the same therefrom. The base-board 66 of the seat may be suitably padded at 75 and covered, as desired, at 76.

Where the seat 65 and adjustable or extensible aspect of the foot rest is not desired, the seat 65 and support 40 are removed or left off, and a cross-brace 80 is applied to the upper tubular margins of the box at one end with a pair of angular braces 81 and 82 applied at the opposite end. The cross-brace 80 comprises a generally U-shaped rod of circular section with its opposite angular ends fitting telescopically in the ends of the tubular side margins 32 at one end of the box and secured therein as by chisel punches 84, 84. One leg of each angular corner brace 81, 82 fits telescopically in the end of each margin 32 at the opposite end of the box and is secured therein as by chisel punches at 85, 85. The other legs of the angular corner braces 81, 82 fit telescopically in the opposite ends of the tubular margin 34 and are secured therein as by chisel punches 86, 86. One leg of each corner brace 81, 82 is preferably relatively short to permit convenient application of these braces by springing the tubular margins of the box slightly.

The foot rest 56 in this instance has a downwardly curved arm 57 terminating at its lower end in an angular bracket 88 resting upon the tubular end margin 34 and clamped to the doubled upper end of the end wall 12 by a bolt 90. The foot rest is thus clamped directly and rigidly to the upper margin of the end wall of the box and the corner braces 81, 82 impart the desired strength against the stresses which may be imposed thereon when the foot is placed upon the foot rest 56.

For the purpose of securing the extensible support 40 of the embodiment shown in Figs. 1 to 6, a suitable spring stop 92 may be provided for one of the horizontal ends 43. Of course, a similar stop may be provided at the opposite side, if desired. The stop illustrated is shown as having a pair of arms 93 extending laterally from the top of one side of the box, the rod 43 extending through the inner ends of these arms 93 which are urged apart and into frictional engagement with the rod 43 as by means of a spring 95 to hold the support 40 in any desired position. The outer ends of the arms 93 form finger pieces which may be grasped and forced together to release the frictional engagement of the inner ends of the arm with the rod 43 and permit free sliding movement of the support 40. The foregoing stop is along the line employed in connection with transom rods and the like, as well understood in the art.

I claim:

1. In a device of the class described, a base, a box mounted upon said base, tubular

- 5 margins at the top of the box, and a foot rest having a support engaging telescopically in said margins for extension and retraction into different positions and for application to and removal from said box.
- 10 2. In a device of the class described, a base, a box mounted upon said base, marginal beads at the top of the box and a removable and adjustable seat adapted to fit over the top of the box, said seat being provided with depending flanges having sliding engagement with said marginal beads and interlocked with said beads against upward removal from the box.
- 15 3. In a device of the class described, a base, a box mounted upon said base, tubular margins at the top of the box, a foot rest having a support telescopically engaging said margins for extension and retraction into different positions and for application to and removal from the box, and a removable and adjustable seat adapted to fit over the top of the box, said seat being provided with depending flanges having sliding engagement with said tubular margins and interlocked with said tubular margins against upward removal from the box.
- 20 4. In a device of the class described, a base, a box mounted upon said base, tubular margins at the top of the box, and a foot rest support comprising a generally U-shaped rod having vertical leg portions with its base arched therebetween, and the legs of said support being turned at substantially right angles and engaging telescopically in said margins for extension and retraction into different positions and for application to and removal from the box.
- 25 5. In a device of the class described, a base, a box mounted upon said base, tubular margins at the top of the box, and a foot rest support comprising a generally U-shaped rod having vertical leg portions with its base arched therebetween, and the legs of said support being turned at substantially right angles and engaging telescopically in said margins for extension and retraction into different positions and for application to and removal from the box, a cross-piece
- 30 6. In a device of the class described, a base, a box mounted upon said base, tubular margins at the top of the box, and a foot rest support comprising a generally U-shaped rod having vertical leg portions with its base arched therebetween, the legs of said support being turned at substantially right angles and engaging telescopically in said margins for extension and retraction into different positions and for application to and removal from the box, and a removable and adjustable seat adapted to fit over the top of the box, said seat being provided with depending flanges having sliding engagement with said tubular margins and interlocked with said tubular margins against upward removal from the box.
- 35 7. In a device of the class described, a base, a sheet metal box secured at its bottom upon said base and open at one end, the upper ends of the opposite sides and end walls of the box being rolled back to form tubular margins, an extensible foot-rest support having telescopic engagement with the tubular side wall margins, and a removable seat slidably mounted upon said side wall margins.
- 40 8. In a device of the class described, a base, a sheet metal box secured at its bottom upon said base and open at one end, rolled back tubular margins along the upper edges of the side walls of said box, and a rolled back tubular margin along the upper edge of the end wall of said box.
- 45 9. In a device of the class described, a base, a sheet metal box secured at its bottom upon said base and open at one end, rolled back tubular margins along the upper edges of the side walls of said box, a rolled back tubular margin along the upper edge of the end wall of said box, an outwardly pressed bead in the walls of said box, and a shelf having marginal flanges secured in the internal depression formed by said bead.
- 50 In witness whereof, I hereunto subscribe my name this 26th day of March, 1927.
- JOSEPH SILVERMAN.
